UNITED STATES PATENT OFFICE.

PELL WILLIAM FOSTER, OF NEW YORK, N. Y., ASSIGNEE TO POWER SPECIALTY COMPANY, OF NEW YORK, N. Y., A CORPORATION OF NEW YORK.

GARBAGE-DESTRUCTOR.

1,159,371.

Specification of Letters Patent.

Patented Nov. 9, 1915.

Application filed March 17, 1914. Serial No. 325,223.

To all whom it may concern:

Be it known that I, PELL W. FOSTER, a citizen of the United States, residing at New York, in the county and State of New York, have invented certain new and useful Improvements in Garbage-Destructors, of which the following is a full, clear, and exact description.

The invention which forms the subject of this application for Letters Patent is an improvement in garbage destructors, and is concerned with means for the better operation and protection of such apparatus while in use.

I have found in these destructors when provided with a shifting grate which is periodically withdrawn to dump a charge of hot clinker into a cooling chamber, that the air blast which is usually forced up through the mass of incandescent clinker for the purpose of cooling the same and providing a forced draft for the ignition and combustion of a fresh charge of combustible material, reaches the furnace chamber for a short time, at least, at too high a temperature, is liable to injure the grate and develop too great a heat within the device and is sometimes impeded by the mass of clinker.

One of the objects of my invention is to avoid these objections, for which purpose I provide a series of fuses or boxes forming the side walls of the clinker cooling chamber and constituting paths by which the air supplied for cooling the clinker and promoting combustion is conveyed around and not through the body of hot clinker and distributed over the same in the space under the grate bars. In this way the draft of air, while highly heated, is not raised to an objectionably high temperature, as it would be by passing directly through the incandescent clinker, is not deprived to the same extent of its combustion supporting properties, and is always free to reach the grate bars through unobstructed passages, which is not the case when it is forced through the bed of clinker, which may be more or less solid and impervious.

Another defect in these destructors I have found to be the result of the stoppage of the air circulation through the curb or lining of the fire box, when the operation of the device is interrupted and the fires banked. Under ordinary conditions, the fire box lining is protected by passing through it the

air which is utilized to support the combustion of a fresh charge of material, but when the operation of the furnace is temporarily interrupted, the banking of the fires requires that this draft be shut off and the heat of the fire is then sufficient to burn out or injure the curb of the furnace. To avoid this result I have provided the air passage from the hollow curb with two controllable branches, one leading to the clinker cooling chamber and the other to the outside air, so that when the fire is banked the draft through the curb may be maintained without furnishing air to the fire.

Other improvements in the construction of the device which I have devised have resulted from experience and observation of the operation of destructors of this kind. For example, the sides of the curbs above and around the grate bars are made upwardly and inwardly instead of outwardly inclined to facilitate the discharge of the clinker when the grate is withdrawn, and to prevent the arching of the clinker, which, with outwardly inclined curbs which sometimes formed a skewback inducing the arch, was liable to occur.

Again, I may employ in the clinker cooling chamber an inclined grate to receive the charges of clinker, and to retain the clinker in position while cooling. In such case I use a hinged plate or lip which forms a stop for the clinker when turned up, and a slide or chute for the discharge of the same, into a car or other receptacle, when turned down.

Another improvement resides in forming openings in the side walls of the hollow curb through which a part of the air forced through these curbs may escape and impinge upon the ends or upon such portions of the grate as are liable to become overheated and injured, and still another improvement consists in securing the castings of the curb together by through bolts, the ends of which are extended out through the wall of the destructor and provided with short springs which take up and compensate for any expansion of the bars that may result from the intense heat to which they are subjected.

These improvements are illustrated in the accompanying drawing, in which I have shown in Figure 1 the destructor in central vertical section; in Fig. 2 a detail of the curb construction; and in Fig. 3 a portion of the curb with the openings therein.

In previous patents and applications, I have shown destructors of the general type here employed, comprising a grab-bucket A, which brings charges of garbage and refuse 5 to the device and delivers them into a chute or hopper B. From this the material is allowed to drop through a hydraulically operated door G into the fire box or combustion chamber D, in which it is ignited either 10 by fuel or by the heat of the chamber itself.

In the lower part of the combustion chamber, immediately above the grate bars, is a hollow curb E, the inner walls of which incline upwardly and inwardly, that is to 15 say, the curb is widest at the top, for the reasons above set forth. This curb forms a continuous passage for air or steam, and is provided with an inlet F from a fan or blower, of either hot or cold air or a source 20 of steam, and an outlet G from the middle of its rear end which extends down into an air chamber H. From the latter there runs a passage K into the clinker cooling chamber, containing a valve L and a second passage M to the outer air, containing also a 25 valve N.

I may use any form of clinker grate or hearth, but in this particular device I use an inclined grate O to receive the charges 30 of clinker. At the bottom of such a grate I place a rotating flap or lip P, controlled by hand, which normally holds the clinker on the grate, but which, when turned down as shown in dotted lines, when the door R 35 is opened, forms a chute over which the clinker slides from the grate into a car or other receptacle S.

The charges of material when practically 40 burned out in the fire box are deposited by the withdrawal of the grate bars T in the form of a mass of clinker, onto the grate bars O, and in previous forms of destructor the air for burning the next charge of material was forced up from the space beneath 45 the grate, through the mass of hot clinker to the grate bars T.

For reasons which I have above explained, this is objectionable, and I therefore provide along the walls of the clinker cooling 50 chamber a series of boxes or flues V open to the space below the grate bars O and provided with a large number of holes W at their upper ends. The forced draft passes up through these boxes, is distributed by the 55 holes into the space beneath the grate, gradually cooling the clinker, and then passes up through the fire. In this way the air is heated before it reaches the fire, while at the same time the walls of the clinker chamber 60 are cooled and protected from injury.

The curb E is composed of sections of cast iron or steel, which are held together by through bolts Y, in the usual manner, but the ends of these bolts extend out entirely 65 through the walls of the destructor where

they are provided with nuts between which and the side wall or plates thereon are springs X which relieve the destructive temperature strains on the bolts.

In Fig. 3 I have shown in detail one of a 70 number of openings Z, which I provide in the curb or the passage from the same. Air or steam escapes through openings and impinges upon the grate in sufficient amount to protect the same from the injurious effect of the very high temperature to which, 75 in the operation of the device, it is subjected.

The construction of the device, both as regards details and general arrangement, may be very greatly varied, but the specific improvements which I have above described 80 constitute, I believe, the last step which makes for the economy and practicability of the destructor. Practical experience with the use of these devices has demonstrated 85 their great value and importance.

What I claim is:

1. The combination with a furnace and its grate bars adapted for the destruction of garbage, of a hollow curb for the combustion chamber and passages leading to the outer air and to the space below the grate bars, whereby a circulation of air or steam may be maintained through the same and the fire, or through the same into the outer 95 air, as set forth.

2. The combination in a garbage destructor with a combustion chamber, a movable grate and a clinker cooling chamber beneath the same, of a hollow curb for the 100 combustion chamber, and passages from the same having branches leading to the outer air, and to the clinker chamber, as set forth.

3. In a garbage destructor, the combination with a combustion chamber, a clinker 105 cooling chamber beneath the same adapted to receive the clinker discharged from the combustion chamber, and means for cooling the clinker and the walls of the clinker chamber and supplying air or steam to the 110 grate bars of the combustion chamber, comprising a series of boxes or flues located alongside the walls of the clinker cooling chamber and provided with openings into the clinker chamber for the discharge of 115 said air or steam thereinto.

4. In a garbage destructor, a hollow curb composed of castings, in combination with through-bolts securing the same together, the ends of said bolts being extended out 120 through the walls of the device and provided with nuts, and springs interposed between said nuts and the walls to relieve the temperature strains on the bolts.

5. In a garbage destructor, the combination with a combustion chamber, a clinker cooling chamber beneath the same and a grate within the clinker chamber for receiving the clinker discharged from the combustion chamber, of a series of boxes or 130

flues located at the sides of the clinker grate and along the walls of the clinker cooling chamber provided with an inlet opening below the clinker grate and outlet openings 5 above the clinker grate whereby air or steam is conducted from beneath the clinker grate to the grate bars of the combustion chamber.

6. In a garbage destructor, the combination with a combustion chamber, a clinker 10 cooling chamber beneath the same, a grate within the clinker chamber for receiving the clinker discharged from the combustion chamber, and means for cooling the walls of

the clinker chamber comprising a series of boxes or flues located along the walls of the 15 clinker cooling chamber provided with an inlet opening for air below the clinker grate and discharge openings therefor above the same.

In testimony whereof I affix my signature 20 in the presence of two subscribing witnesses.

PELL WILLIAM FOSTER.
